United States Patent Office

Des. 181,346
Patented Nov. 5, 1957

181,346

TUMBLER

Albert J. Dreitzer, New York, N. Y.

Application December 10, 1956, Serial No. 44,144

Term of patent 14 years

(Cl. D36—8)

Fig. 1 is an elevational view of a tumbler showing my new design;

Fig. 2 is a bottom view thereof;

Fig. 3 is a fragmentary cross-sectional view substantially along the line 3—3 of Fig. 1; and

Fig. 4 is a cross-sectional view substantially along the line 4—4 of Fig. 1.

I claim:

The ornamental design for a tumbler, substantially as shown.
